(57) **CLAIM**

The ornamental design for a cartridge drive, as shown and described.

DESCRIPTION

FIG. 1 is a perspective view of a cartridge drive showing my new design;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a rear view thereof.

The broken line showing of the rectangular portion within the other broken lines represent the bounds of the claimed design while all other broken lines are directed to unclaimed portions of the cartridge drive; the broken lines form no part of the claimed design.

1 Claim, 3 Drawing Sheets
